SPOOL WINDER FOR SEWING MACHINES

Hermann Zink and Herbert Wenz, Kaiserslautern, Germany, assignors to G. M. Pfaff A.-G., Kaiserslautern, Germany, a corporation of Germany

Application May 6, 1953, Serial No. 353,370.

Claims priority, application Germany May 9, 1952

2 Claims. (Cl. 112—218)

The invention relates to sewing machines, and relates more particularly to a novel type of equipment for winding thread on a spool powered by the hand wheel of the sewing machine.

Modern sewing machines are characterized by a high degree of streamlining of the upper casing. This not only caters to modern taste, but also has the advantage that there are hardly any parts protruding which, during covering and uncovering of the machine head, for instance in connection with portable sewing machines, are liable to be struck by the cover.

The instant invention provides a winding device that is recessed in the machine housing and has only two small protruding parts, to receive the spool for winding thread thereon.

It is among the objects of the invention to provide a spool winding mechanism, the major parts of which are concealed, and that can easily be actuated for engagement by the hand wheel, and which has provisions for deactivation after a predetermined amount of thread has been wound onto the spool.

With the above and other objects of the invention in view, the invention consists in the novel construction, arrangement and combination of various devices, elements and parts, as set forth in the claims hereof, certain embodiments of the same being illustrated in the accompanying drawings and described in the specification.

The foregoing and other objects of the invention will be best understood from the following description of exemplifications thereof, reference being had to the accompanying drawings, wherein:

Fig. 1 is an elevational view of a sewing machine with a spool winder in accordance with the invention;

Fig. 2 is a large-scale fragmentary plan view, seen in direction 2—2 of Fig. 1, the top cover having been removed, showing the device in the active, winding, position;

Fig. 3 is a fragmentary sectional view taken along the irregular secant line 3—3 shown in Fig. 2, illustrating the device in winding position;

Fig. 4 is a perspective view of the device removed from the sewing machine housing;

Fig. 5 is an elevational view, partly in section, taken on line 5—5 of Fig. 2; and

Fig. 6 is a fragmentary plan view, similar to Fig. 2, but showing all the parts in rest position.

Sewing machine.—In carrying the invention into effect in one of the embodiments which has been selected for illustration in the accompanying drawings and for description in this specification, and referring now particularly to Fig. 1, there is provided a sewing machine 21, for instance of the portable type, that has a housing 22. At the right side of the housing 22, there is disposed a conventional hand wheel 23, and the housing 22 is surmounted by a cover 24. Below the cover 24 there is provided a spool winding mechanism generally indicated at 26, the major portion of which is concealed below the surface of the cover 24, all as shown in Fig. 1.

The spool winding device 26, as best shown in Figs.

2

2—6, comprises a base plate 27 that is removably mounted on the sewing machine structure 28.

Spool carrier.—On the base 27 there is pivotally supported a spool carrier 29. The spool carrier 29 comprises an offset lever 31 that is pivoted with one end to the base 27 by means of a screw 32, and a spiral spring 33 (Fig. 3) is provided concentrically with the screw 32 which tends to turn the lever 31 in the direction B. At the free end of the lever 31 there is secured a bearing 34 (Fig. 5) which journals a vertical freely rotatable shaft 36.

The shaft 36 includes near its lower end a wheel 37 that is rotatable with the shaft 36 and which carries an annular hand wheel engaging member such as a rubber ring 38; the shaft 36 includes near its upper end a flange 39 that is rotatable with the shaft 36 and which carries an eccentric spool engaging pin 41 and a central spool carrier pin 42. A spool 43 on which there is to be wound a thread 44 may removably be inserted over the pin 42 to rest on the flange 39 while the pin 41 engages an aperture in the spool 43.

The lever 31 has a recess 46 (Figs. 2 and 4) that faces inwardly of the machine (towards the left in Fig. 2) and which is disposed about midway of the length of the lever and has inclined surfaces. Adjacent the inclined surfaces of the recess 46 the lever 31 is provided on the inner side with a straight flat surface 47.

The spring 33 normally urges the lever in the direction B towards a rest position (Fig. 6) in which the rubber ring 38 is out of contact with the hand wheel 23.

Control lever.—On the base 27 there is furthermore pivoted a control lever generally indicated at 48, which is pivoted to the base 27 by means of a screw 49. Concentric with the screw 49 (Fig. 3) there is mounted a spiral spring 51 that is similar to the aforementioned spring 33. However, the spring 51 tends to turn the lever 48 in the direction A; oppositely relative to the bias that is applied by the spring 33 to the spool carrier 29.

The lever 48 has a hollow section 52 in which there is reciprocably slidable a piston 53 between two opposite end positions. These end positions of the piston 53 are defined by an elongated slot 54 that is formed in the wall of the hollow section 52 and by a pin 56 that is carried by the piston 53 and which protrudes through the slot 54.

A helical spring 57 is disposed in the hollow section 52 inwardly of the piston 53 and the spring 57 urges the piston 53 outwardly in direction C (Fig. 2) towards a position of maximum extension from the hollow section 52.

As best shown in Fig. 2, the piston 53 has a flat front surface with which, in the active winding position, it engages throughout the distance "a" a portion of the flat surface 47 of the lever 31. The inclined surface of the recess 46 forms a cam for engagement by a cam follower nose 55, that is formed on the hollow section 52, during movement of the control lever 48, by the operator, from the rest position to the active position for setting the carrier 29.

Furthermore, the lever 48 includes an upright section 58, that has a terminal section 59 which is bent towards the pin 42 of the spool carrier 29, as best shown in Fig. 2, and the outward bend between the sections 58 and 59 has a recess 61 for easy grasping by the finger of a hand.

A stop 62 is provided on the base 27 to limit the swinging of the lever 48 in direction A, thereby defining the rest position of the lever 48 (Fig. 6).

In the active spool winding position, as best shown in Fig. 5, the terminal section 59 of the lever 48 is spaced from the external surface of the pin 42 for a distance "b." This distance "b" corresponds to a certain amount of thread-winding on the spool 43, close to the maximum

amount of winding desired, and additional winding of thread 44 will cause the lever 48 to be swung against the bias of the spring 51 about the pivot of the screw 49 until the piston 53 completely slides off the flat surface 47. By this sliding-off, the abutment contact between the piston 53 of the lever 31 will be released, permitting the piston 53 to project into the recess 46 of the lever 31, and thereby enabling the carrier 29 to be swung by the spring 33 about the pivot of the screw 32. In this manner, all the parts will assume the rest position (Fig. 6).

Operation.—The operation of the above-described device is as follows.

When it is desired to wind thread on a spool, the spool 43 is inserted over the pin 42 onto the flange 39 of the shaft 36 with a hole of the spool bottom in registry with the pin 41. Thereafter, the operator will press the lever 48 in direction B, for instance by applying finger pressure at the recess 61. Before the pressure is applied, the apparatus will be at the rest position as shown in Fig. 6 wherein the rubber ring 38 is spaced from the hand wheel 23, and the piston 46 is disposed in the recess 46 of the lever 31.

The application of the finger pressure will move the lever 48 in direction B against the bias of the spring 51. During this move, the nose 55 of the hollow section 52 for the piston 53 will glide along the lateral surface of the lever 31 until the piston 53 engages with its flat face the flat surface 47 thereof throughout the distance "a." During this movement, the spring 57 will be compressed and tensioned by the retraction of the piston 53 caused by the sliding thereof on the lateral surface of the lever 31. This movement will cause the carrier 29 to be swung about its pivot in direction A against the bias of its spring 33. In the final position, the rubber ring 38 will abut against the hand wheel 23, as shown in Fig. 2.

The springs 33, 51 and 57 are so dimensioned that in the active position shown in Fig. 2 the engagement between the piston 53 and the flat surface 47 of the lever 31 will be maintained until release is effected.

The hand wheel 23 is then started and the winding of the thread 44 onto the spool 43 begun and continued in the usual conventional manner. The guiding of the thread 44 onto the spool 43 may be done in any conventional manner known to the art, such as either manually or by means of a reciprocating guide, and since this does not form part of the invention this is neither described nor shown in detail.

Continued winding will provide the spool 43 with a layer of thread windings. When the layer reaches a predetermined thickness, the external surface thereof will make contact with the inner surface of the terminal section 59 of the lever 48. Such contact will be made when the thickness of the thread layer added to the thickness of the spool body reaches the distance "b" (Fig. 5). Further thread winding will result in a pushing by the increasing thread layer against the terminal section 59 causing a pivotal movement of the lever 48 in direction A. This pivotal movement is continued throughout the extent of the distance "a" (Fig. 2), after which the piston 53 will glide off the flat surface 47 and slide along the inclined surface adjacent thereto of the recess 46, until the lever 48 abuts the stop 62. This movement is aided by the spring 51.

During this movement of the lever 48, after the piston 53 has slid off the flat surface 47, the spring 33 will turn the carrier 29 in the direction B, thereby releasing the abutment contact between the rubber ring 38 and the hand wheel 23. The parts will come to rest as shown in Fig. 6, and the spool 43 may be removed off the pin 42.

The device shown in Figs. 2-6 may be built separately, and thereafter mounted on the finished sewing machine. For the assembly, there are provided elongated slots 63 in the base 27 so that the base 27 may be adjustably mounted by means of screws 64 that protrude through the slots 63.

The cover 24 is provided with an aperture 66 through which may protrude, of the entire device 26, only in the pin 42 and the flange 39 as well as the upright section 58 and the terminal section 59 of the lever 48.

By this arrangement, the streamlined appearance of the sewing machine head is preserved, and the chances minimized for damage during movement on and off the machine of a cover.

It will be apparent to those skilled in the art that the novel principles of the invention disclosed herein in connection with specific exemplifications thereof will suggest various other modifications and applications of the same. It is accordingly desired that in construing the breadth of the appended claims they shall not be limited to the specific exemplifications of the invention described herein.

Having thus described the invention, what we claim as new and desire to be secured by Letters Patent, is as follows:

1. In a spool winding device, for use in connection with a sewing machine having a hand wheel and an apertured cover, in combination, as elongated cranked spool carrier member pivoted for arcuate movement in opposite directions between an inactive rest position, and an active position wherein it is in driven connection from said hand wheel, and including a spool support, a spring urging said carrier member towards said inactive position, a control member pivoted for arcuate movement in opposite directions between an active carrier engaging position and a rest position wherein it is disposed substantially perpendicularly to said spool carrier member, resilient means urging said control member towards said rest position, and means intermediate said members comprising a cam surface formed on said carrier member opposite the pivot of said control member and including a first flat surface, a second flat surface and an intermediate surface, a follower formed fixedly on said control member and being operable to engage said intermediate surface when said control member is moved from the rest position towards the engaging position thereby moving said carrier from the inactive to the active position, and a plunger movably disposed in said control member adjacent said cam follower thereof and being spring pressed towards ejection from said control member and having a flat face disposed at an angle to said cam follower and being operable to engage in abutment said first flat surface in the active position and operable to engage in abutment said second flat surface in the rest position.

2. In a device, as claimed in claim 1, said cover extending to a height slightly inferior to that of said carrier and of said control lever, the top portion of said carrier and of said control lever protruding through the aperture of said cover and extending beyond the external surface of the cover, said cover concealing all other portions of said carrier and control lever.
